No. 783,569.

PATENTED FEB. 28, 1905.

P. EDLICH.
MERCERIZING APPARATUS.
APPLICATION FILED JULY 15, 1903.

UNITED STATES PATENT OFFICE.

PAUL EDLICH, OF TRIEBES, GERMANY.

MERCERIZING APPARATUS.

SPECIFICATION forming part of Letters Patent No. 783,569, dated February 28, 1905.

Application filed July 15, 1903. Serial No. 165,705.

To all whom it may concern:

Be it known that I, PAUL EDLICH, a subject of the German Emperor, residing at Triebes, Germany, have invented certain new and useful Improvements in Mercerizing Apparatus, of which the following is a specification.

This invention relates to an apparatus for mercerizing cotton fabric wherein the fabric is passed uninterruptedly through the initial tension-machine, then through the proper mercerizing device, and then through the final tension-machine. While with the known machines relating to this art the fabric as soon as it leaves the initial tension-machine has to be transported by hand to the mercerizing device proper and after going through the same has to be transported by hand to the final tension-machine, the present invention provides for a continuous treatment of the fabric in these several apparatus, which have been combined in one mechanical combination.

In the annexed drawing the apparatus is partially represented in vertical section and partially in side view. It consists of three main parts—to wit, the preliminary tensioning-machine B, the real mercerizing-machine C, and the widening-machine D. Eventually the padding-machine A may be arranged in front of the whole apparatus. These main parts are combined to an organic whole in such a manner that the fabric may pass them without interruption, and in consequence thereof such treatment of the fabric is rendered much cheaper and more rapid than was hitherto the case. Furthermore, the fabric is prevented from contact with the hands of the attendants, and consequently its quality cannot suffer any loss. The fact that the fabric is subjected to a tension lengthwise and crosswise in the final tension-machine immediately after leaving the mercerizing device proper produces an extraordinary sheen on the same which cannot be produced by any of the existing machines for purposes of this kind. The parts A and B correspond with the known single arrangements of such art; but the mercerizing device C and the final tension-machine D differ materially from former arrangements of the same kind. The mercerizing device C consists

of the trough 20, which has a double bottom in 50 which cold water is pumped to keep the lye cool. In the trough 20 are the dipping-rollers 15 16, and in the upper part of the trough are stretching-rollers 21 23. Over the trough 20 are four pressure-rollers 24, 25, 26, and 27, 55 arranged one above the other, of which 24 and 26 can be heated by means of steam or an electric current. The rollers 24 and 26 are made of cast-iron, as are also the rollers 25 and 27; but the latter are coated with hard 60 rubber. The final tension-machine D is arranged in such a way that the fabric in passing through the same is formed into vertical tension-fields, for which purpose the rollers 31, 32, 34, 35, and 37 serve. In this manner 65 the route of the soaked fabric through the final tension-machine can be made longer to any required extent, according to the nature of the fabric which is being treated, without the weight of the tension-chain required for 70 such longer route requiring more power, because such additional weight will be completely counteracted by the vertical tension-fields and will therefore not increase the resistance.

The action of the apparatus is as follows: The fabric wound upon the roller 1 is conducted, through the guide-rollers 2 3 4 5, into the trough 6, containing finishing matter, then travels between the rollers 7 8, over the guide-roller 9, through the trough, and arrives, through the rollers 8 10 and guide-roller 11, into the preliminary tensioning-machine B. At 12 the material is inserted into the grippers or clamps of the chain and tensioned to about 80 three inches beyond its normal width. Thus prepared the material leaves the tensioning-machine at 13 to pass into the mercerizing arrangement C. Thereby it travels over the roller 14, the dipping-rollers 15 16, and the 85 rollers 17 18 19, the roller 18 equalizing the longitudinal pull on the fabric between the apparatus B and D—that is to say, it yields when the fabric is pulled too taut and tensions up if the material is slack. For this purpose 90 the said roller 18 is so arranged that it can be automatically adapted as to height—*i. e.*, can be moved up or down. From the guide-roller

19 the fabric which in the apparatus C has lost about two to three inches of the excess width required in the tensioning-machine B, passes to the stretching-rollers 21 22 23 and 5 then passes over the pressure-rollers 24 25 26 27, the powerful perpendicular pressure of which assists the lye to thoroughly penetrate the fibers. The rollers 24 and 26 may be heated by steam, electric current, or the like, 10 as mentioned above, if the material is to receive a dull wool-like appearance instead of a silk-like sheen. This will heat the fabric passing through these rollers, whereby the lye contained in the same will partially dry 15 out and concentrate, producing a loosening and raising up of the cotton threads, so that the fabric obtains a hairy surface and a woolly appearance. This also makes the fabric more elastic. The rollers 24 and 26 are of cast-iron, 20 as are also the rollers 25 27; but the latter can be provided with resilient coverings of vulcanite to increase their efficiency. During the passage of the material from the pressure-rollers of the mercerizing apparatus C to the 25 widening-machine D the longitudinal tension between C and D is equalized by the ascending and descending roller 28. The fabric is again picked up by tensioning-chains at 29 30 and again stretched to a width of, say, three 30 inches. These and the other measures referred to are of course only mentioned as approximate examples. Thus very tightly stretched the fabric passes through the machine D, over the long path 30 31 32 34 35, and through the 35 rinsing-trough 36, in which it is squirted on both sides. The fabric leaves the tensioning-chain at 37 and is freed from its remaining moisture by passing between pressure-rollers, after which it is delivered by the folder 38 40 and laid on the truck 39.

Having now fully explained my invention, I declare that what I claim is—

1. In an apparatus for continuously mercerizing cotton fabric, the combination of a padding device, a preliminary tensioning device 45 to which the fabric passes directly from the padding-machine, a mercerizing device proper which receives the fabric directly from the padding-machine provided with a trough containing mercerizing fluid, means for conducting the fabric through said fluid, of drying-rollers through which the fabric is adapted to pass as it leaves said trough, of means for heating said drying-rollers and a final tension-machine 50 for widening the fabric as it is passed from the mercerizing device.

2. In an apparatus for continuously mercerizing cotton fabric, the combination of a padding device, a preliminary tensioning device 60 to which the fabric passes directly from the padding-machine, a mercerizing device proper which receives the fabric directly from the padding-machine provided with a trough, a double bottom for said trough through which

water may be pumped to cool the mercerizing fluid and a final tension-machine for widening the fabric as it is passed from the mercerizing device. 65

3. In an apparatus for continuously mercerizing cotton fabric, the combination of a padding device, a preliminary tensioning device to which the fabric passes directly from the padding-machine, a mercerizing device proper which receives the fabric directly from the padding-machine provided with a trough, a double bottom for said trough through which water may be pumped to cool the mercerizing fluid, means for conducting the fabric through said fluid, of drying-rollers through which the fabric is adapted to pass as it leaves said trough, of means for heating said drying-rollers and a final tension-machine for widening the fabric as it is passed from the mercerizing device. 70 75 80

4. In an apparatus for continuously mercerizing cotton fabric, the combination of a padding device, a preliminary tensioning device to which the fabric passes directly from the padding-machine, a mercerizing device proper which receives the fabric directly from the padding-machine provided with a trough containing mercerizing fluid, means for conducting the fabric through said fluid, of drying-rollers through which the fabric is adapted to pass as it leaves said trough, of means for heating said drying-rollers and a final tension-machine for widening the fabric as it is passed from the mercerizing device, of a rinsing-trough through which the fabric travels on leaving the final tension-machine, means of squirting the fabric on both sides when passing said trough and means of removing the remaining moisture from the fabric after leaving said trough. 85 90 95 100

5. In an apparatus for continuously mercerizing cotton fabric, the combination of a padding device, a preliminary tensioning device to which the fabric passes directly from the padding-machine, a mercerizing device proper which receives the fabric directly from the padding-machine provided with a trough containing mercerizing fluid, means for conducting the fabric through said fluid, of drying-rollers through which the fabric is adapted to pass as it leaves said trough, of means for heating said drying-rollers and a final tension-machine for widening the fabric as it is passed from the mercerizing device, of a rinsing-trough through which the fabric travels on leaving the final tension-machine, means of squirting the fabric on both sides when passing said trough, and pressure-rollers through which the fabric passes when leaving said trough. 105 110 115 120

6. In an apparatus for continuously mercerizing cotton fabric, the combination of a padding device, a preliminary tensioning device to which the fabric passes directly from the

- padding-machine, a mercerizing device proper which receives the fabric directly from the padding-machine provided with a trough, a double bottom for said trough through which water may be pumped to cool the mercerizing fluid and a final tension-machine for widening the fabric as it is passed from the mercerizing device, of a rinsing-trough through which the fabric travels on leaving the final tension-machine, means of squirting the fabric on both sides when passing said trough and pressure-rollers through which the fabric passes when leaving said trough.
7. In an apparatus for continuously mercerizing cotton fabric, the combination of a padding device, a preliminary tensioning device to which the fabric passes directly from the padding-machine, a mercerizing device proper which receives the fabric directly from the padding-machine provided with a trough, a

double bottom for said trough through which water may be pumped to cool the mercerizing fluid, means for conducting the fabric through said fluid, of drying-rollers through which the fabric is adapted to pass as it leaves said trough, of means for heating said drying-rollers and a final tension-machine for widening the fabric as it is passed from the mercerizing device, of a rinsing-trough through which the fabric travels on leaving the tension-machine, means of squirting the fabric on both sides when passing said trough and pressure-rollers through which the fabric passes when leaving said trough.

In testimony whereof I affix my signature in presence of two witnesses.

PAUL EDLICH.
